HAIR CURLER

William H. Schmitt, St. Paul, Minn.

Application July 12, 1935, Serial No. 31,015

14 Claims. (Cl. 132—33)

My invention relates to hair curlers wherein it is desired to provide a curler of a simple character which may be easily attached to the locks of hair and which is adapted to more firmly engage the hair wrapped about the same so that the curler will stay in place until it is desired to remove it.

A feature resides in providing a tubular curler to which is pivotally secured a clamping member adapted to engage the ends of the locks of hair and a slideable locking and releasing means which operates to hold the clamp locked in one position and to release the same in another position. The slideable locking and releasing means is of a resilient nature and is formed with a free end which extends over the free end of the clamping member which is pivoted to the tubular member. When this releasing and locking means is slid over the tubular member, it locks the clamp against opening by a positive bridge across the end of the slideable releasing and locking means. When the releasing and locking means is slid into releasing position, then the resiliency of the same permits the clamp to be opened against the resiliency of the releasing and locking means, which provides the spring means for normally holding the clamp on the tubular member closed.

My curler may be provided with a separate spring means for holding the clamp normally closed, and in addition, provided with the slideable releasing and locking means which slides over the clamp to hold the strands of hair which have been wrapped around the tubular member into curling position and from coming off of the curler or from unwinding on the same.

A feature of my curler resides in a structure of a simple nature, where the clamp may be released by a longitudinal movement of the releasing and clamping means. Then the ends of the strands of hair may be engaged under the clamp and the hair wound around the clamp and tubular member, and then by a simple longitudinal movement, like the pushing of a bobby-pin over the strands of hair, or a hairpin into the hair, the releasing and locking means is pushed home into locking position which engages over the hair on the curler to hold the same in place until the hair is curled to the desired extent.

These features and other details and objects will be more fully and clearly set forth in the specification and claims.

In the drawings forming part of this specification;

Figure 1 is a side elevation of a form of my curler.

Figure 2 is a plan view of the curler illustrated in Figure 1.

Figure 3 is a section on the line 3—3 of Figure 2.

Figure 4 is a perspective view of another form of my curler, where a flat, slideable releasing and locking means is provided.

Figure 5 illustrates another form of my curler in side elevation.

Figure 6 is a section on the line 6—6 of Figure 5.

Figure 7 is a perspective view of another variation of my curler.

Figure 8 is a section on the line 8—8 of Figure 7.

Figure 9 illustrates a different form of my curler.

Figure 10 illustrates a side elevation of another form of my curler.

Figure 11 is a perspective view illustrating the slideable resilient locking and releasing means used in the form of my curler illustrated in Figure 10, formed of round wire, the same being removed from the other connecting members of the curler.

Figure 12 illustrates a perspective view of a flat wire spring releasing and locking means, removed from the other members of the curler.

Figure 13 illustrates another form of my curler.

Figure 14 is a section on the line 14—14 of Figure 13.

Figure 15 is a side view of another alternate type of curler.

Figure 16 is a top plan view of the curler illustrated in Figure 15.

Figure 17 is a section on the line 17—17 of Figure 16.

Figure 18 is a section on the line 18—18 of Figure 16.

I have illustrated my hair curler A formed with a perforated tubular member 10 which is adapted to form the tube around which the locks of hair are adapted to be wrapped. This tube 10 is formed with air circulating openings 11. The curler A is provided with a clamping member 12 which is also formed with air circulating perforations 13 and which is pivotally attached at 14 to one end of the tubular member 10 so that the clamping member 12 may be hingedly supported to the tubular member 10 so that the free end 15 of the same may be moved into the dotted line position illustrated in Fig-

ure 1 to permit the ends of the locks of hair to be engaged thereunder.

The curler A is provided with a releasing and locking spring member 16 which may be formed of round wire. The releasing and locking member 16 when formed of wire, as indicated in Figures 1 and 2, is adapted to be bent to form the spring wire arms 17 formed by parallelly extending portions which form these arms and which have an upturned tongue end 18 over the locks of hair which have been wound around the tubular member 10 and the channel shaped clamping member 12 when the releasing and locking member 16 is moved longitudinally into locking position with the arms 17 extending over the tube 10. In this position, the member 16 holds the curler A locked closed over the locks of hair so as to hold the same from coming off of the curler and to keep the hair from uncurling.

The slidable releasing and locking means 16 is supported to the curler A by means of the loops 19 formed at the rear portion of the clamping member 12 and on the tubular portion 10. These loops 19 slidably support the spring arms 17 so that the same will be guided over the lower side of the tubular member 10 and over the top of the clamping member 12, to lock the clamp 12. The releasing and locking member is formed with a bridge portion 20 which connects one end of the arms 17. The bridge portion 20 is formed in a manner to provide finger engaging loops 21 on either side of the same which facilitate the easy engagement of the bridge to slidably move the arms 17 in the loops 19 to release or lock the clamp 12.

In operation the curler A is engaged and the releasing and locking means 16 is drawn out into the approximate position shown in Figure 1, and then by pressure on the spring arms 17 the same are bent inwardly toward each other as indicated in dotted outline which opens the curler by separating the clamp 12 from the tube 10, as indicated in dotted outline. This permits the curler to be easily opened by the simple pressure on the pins of the spring arms 17, and the end of the locks of hair to be wound around the tube 10 and clamped under the member 12. The pressure is then released on the spring arms 17 and the hair is wound around the tubular member and clamp 12 to the desired extent, and then by the simple operation of pressing inwardly on the bridge 20, of the releasing and locking means 16, the arms 17 are forced over the hair which has been wound around the curler. This operation is similar to the force of a hair or bobby-pin over the hair and is a natural, easy operation for the user of the curler A. When the releasing and locking means is pushed home into this locking position, the bridge 20 forms a rigid locking means which prevents the opening of the clamping member 12 as well as providing the necessary spring engaging means over the hair wound on the curler. Thus the curler is held firmly in place so that the hair cannot unwind on the same.

My curler A is of a simple construction having a compact nature so that it will fit closer to the head of the wearer than former types of curlers, because there are no wide spread overlapping portions for locking the hair in place wound around the curler tube. The spring arms fit closely over the hair and are locked firmly in place.

In Figure 4 I have illustrated my curler B with the perforated tubular portion 10 and the clamp-

ing member 12 hinged at 14. In this construction of my curler, instead of the releasing member 22 being made of round wire, it is made of flat wire and is provided with the flat spring arms 23 which are connected by the bridge portion 24 and which has the projecting finger engaging lips 25 on either side of the bridge. The operation of the curler B is identical to that just described in the curler A. The arms 23 extend under the loops 19 and are slidably supported in operative position to provide a smooth character to the curler B which fits closely to the head of the wearer and holds the hair firmly on the curler.

In Figure 5 I have illustrated another form of my curler wherein the perforated tube 10 operates in conjunction with the clamp 12 and which members are pivotally connected together at 14 to form the body of the curler C. In the curler A the releasing and locking means 26 is formed of wire and is provided with an upper pair of wire arms 27 which extend under the curved loops 28. The arms 27 have a connecting upwardly extending tongue 29 at the free end and are connected at the rear end by the bridge 30 to the lower spring arms 31. The lower spring arms 31 are adapted to extend under the loop 32 which is formed within the rear end of the tube 10 so that the arms 31 slide inside of the tube 10 instead of on the outer surface thereof, as in the former curlers A and B. The operation of this curler is the same as A and B in that the releasing and locking means 26 slides over the tubular core 10 and the clamp 12 into releasing and locking position.

I have illustrated in Figure 7 my curler D which is formed with a tubular perforated core 10 and the clamping channel member 12 which are pivoted together at 14. In this construction, the releasing and sliding member 33 is formed of flat spring wire and has an upper spring arm 34 which is slidably supported under the loop 35. The arm 34 is connected by the bridge 36 to the lower spring arm 37 which slides under the inner loop 38 so as to slidably support the spring arm 37 within the tubular member 10. The bridge 36 is formed with a finger engaging lip 39 which permits easy engagement of the slidable releasing and locking member 33 to operate the same over the tube 10 and the clamp 12.

Figure 8 illustrates a section of the curler D on the line 8-8 of Figure 7, showing the manner in which the parts are connected together.

In Figure 9 I have illustrated a section of a curler E, with a lower tubular portion 10 and the channel clamping member 12 which are pivoted together at 14 in the usual manner as heretofore set forth, and in this construction of the curler E, a suitable spring 40 is looped over the pivot 14 and connected at 41 to the inside of the rear end of the tube 10 and the clamp 12. This spring 40 holds the clamp 12 normally in closed position. In this construction of my curler E, a single slidable releasing and locking member 42 is provided which has a finger engaging end 43 and a spring arm 44 which is slidably supported under the loop 45 formed on the rear upper end of the clamp 12. The arm 45 is formed with an upwardly curved tongue end 46 which guides the same freely over the locks of hair wound around the members 10 and 12.

In Figure 10 I have illustrated the curler F which is formed with the perforated tubular core member 10 and the channel shaped clamping member 12 which are pivotally connected at 75

14. In this form of my curler, the releasing and locking means 47 is formed of spring wire which is bent to form the parallelly extending outer spring arms 48 as illustrated in the formation 5 of the releasing and locking member shown in perspective in Figure 11. The member 47 is formed with inner pairs of spring tongue arms 49 which are adapted to slide inside the hollow tube 10. The outer pairs of spring arms 48 slidably extend under the loops 50 to firmly support the arms 48 slidably operative over the tube 10 and the clamp 12. The arms 48 have curved outer free ends 51 to guide the same over the hair wound around the curler F. In this construction of the releasing and locking means 47 the rear loops 52 act as bridge portions to connect the spring arms 48 with the inner spring loops 49 and to provide the locking means for holding the slidable member 47 in locked 20 position when the arms 48 extend over the tube 10 and the clamp 12.

I have illustrated the slidable releasing and locking means 53 which is made of flat spring wire which is formed with outer spring arms 54 and the inner spring loop 55. This slidable releasing and locking means is of the same character and formation as the member 47, excepting that it is formed of flat spring wire instead of round spring wire.

30 In Figure 13 I have illustrated the curler B which is provided with the tubular core member 10 and the channel clamp 12 which are pivotally connected at 14. The curler G is similar to the curler F in that the slidable releasing and locking means 56 is formed of spring wire with the spring arms 57 and with the inner spring wire loop 58 which is similar to the construction of the slidable releasing and locking means 47. However, in this construction, an inner band coil spring 59 engages within the inner ends of the tube 10 and the clamp 12 to hold the clamp 12 under tension of the spring 59 in normally closed position and not relying entirely upon the springs 57 to hold the clamp 12 closed. Further, the slidable member 56 has an enlarged end 60, shown by dotted lines, formed on the inner end of the spring wire loop 58 which acts to hold the member 56 from disengagement with the tubular member 10, by coming in contact with the band spring 59 in withdrawing or releasing position.

The curler H, illustrated in Figures 15 through 18, differs from the other curlers in that no clamping member 12 is provided in this modification. In the place of the clamping member, I provide a tubular body 62 which is longitudinally slit on either side at 63, through the major portion of the length of the body 62. The slits 63 extend from one end 64 of the body through the major portion of the length of the body. The end 64 of the body 62 is flared outwardly, to guide hair into the slits 63.

The tubular body 62 is longitudinally slit and flattened at the other end 65, and is bent to form an open loop 66, having short sides 67 adjacent the tubular body 62, parallel longitudinally extending sides 68, and abutting ends 69. Spring arms 70, connected to form a handle end 72, extend through openings in the short sides 67 and through the ends 69, and are thus journaled by the loop 66.

In operation, the hair is introduced between the opposed sides of the tubular body 62 in the slits 63, and is wound about the body portion 75 62, while the spring arms 70 are in retracted

position. The spring arms 70 are then urged inwardly over the hair, holding the hair under spring tension against the curler body portion 62.

The character of my hair curlers A, B, C, D, E, F and G, is of the same nature, wherein the formation of the same is of a compact nature with a slidable releasing and locking means which fits closely to the core of the curler and which may be easily operated to release the 10 curler by pulling on the end of the slidable releasing and locking means. This forms a more convenient means for releasing the curler than has been accomplished heretofore. The construction of my curler in its longitudinally extendable form provides a further advantage in 15 making it easy for the operator to engage and attach the same to the hair, because it permits the user or operator to easily attach the ends of the hair under the clamp 12 and then by a 20 simple rotating operation the strands of hair are wound around the curler core to the desired extent and then the curler is locked by pushing the releasing means into locking position. This operation is so simple and effective that it has 25 a very decided advantage over former types of hair curlers.

It is very desirable that a hair curler be easily operated so that it may be quickly attached in position. I have designed my curler so that it 30 will operate in this manner and of a simple, inexpensive, compact construction, so that it may be more economically produced as well as having structural advantages which cause the same to remain firmly in curling position and 35 which will not become entangled with the hair, but which has the advantage of being attached thereto in practically the same easy manner as a hair pin is attached, thus making my hair curler very desirable.

I claim:

1. In a hair curler, a tubular member having holes therethrough, a clamp pivoted to one end thereof and adapted to engage and hold the end strands of hair to be wound on said tubular member, and a slidable clamping member slidably mounted on said tubular member and said clamp and supported substantially parallel thereto adapted to slide over the hair wound on said members to lock the same closed and hold the hair in curling position on said curler.

2. A hair curler comprising a tubular member, a pivoted hair clamp carried by said member, and a slidable hair clamping spring means journaled in said tubular member and in said clamp and longitudinally extending with respect thereto for locking said first clamp closed in one position and acting as a spring to permit the opening of said first clamp under spring tension when in the other position.

3. A hair curler including a tubular member, a channel shaped clamp pivoted to said member, and a slidable locking member journaled on said tubular member and on said channel and longitudinally extending with respect thereto and adapted to lock said clamp closed in one position and acting as a spring closer in another position, permitting the opening of said clamp when said slidable member is in the last position.

4. A hair curler comprising a tubular curling core, a channel clamp pivoted to said core, and a slidable releasing and locking means slidably mounted on said core and on said clamp and adapted to lock said curler closed in one position and to provide a spring means for urging said 75

clamp toward closed position when in releasing position.

5. A hair curler including a tubular core around which the hair is adapted to be wound, and a slideable spring locking member slidably mounted on said core substantially parallel thereto adapted to extend longitudinally over said core to lock the hair around said core.

10. A hair curler including a tubular clamping member having means for engaging the ends of the strands of hair and around which the hair is wound, and a slideable spring clamp slidably mounted on said core and extending substantially parallel thereto, adapted to extend over the wound hair on the curler and having means for locking the curler in closed position to firmly secure the same to the hair.

15. A hair curler comprising a tubular core and clamping means for engaging the ends of the hair to hold the same while the strands of hair are wound around said core and clamping means, and a longitudinally extending slideable releasing and locking means secured substantially parallel to said core adapted to engage over the hair wound on the curler to hold the curler firmly in hair curling position.

20. A hair curler including a tubular core member, a clamp member associated with said core member, a spring loop member including spring arms, and longitudinally extending journal means for slideably supporting said loop member to permit the same to slide longitudinally between two extreme portions over said core and clamping members said loop extending over the hair to 25 lock the same in one extreme position to hold the strands of hair in curling position on said curler, and to be withdrawn from the hair in the other extreme position.

25. A hair curler including a tubular core and clamping means for supporting the strands of hair wound about the same a longitudinally ex-

tending journal means thereon, and a longitudinally slideable resilient locking member extending through said journal having a rigid bridge portion adapted to extend across the end of said curler to lock the same closed.

30. A hair curler including a slideable resilient locking means, a hair receiving core means, and loop means on said core means for longitudinally slideably supporting said locking means to said core means.

10. A hair curler including a pair of relatively pivotal clamping members, each member including a short handle member and a clamping jaw portion, a longitudinal journal in the handle member of each clamping member, and a resilient locking member extending through each journal, said resilient member having arms of sufficient length to lock hair to said clamping jaw portions of said clamping members, and slideable through said journals.

15. A hair curler including a pair of relatively pivotal clamping members, each member comprising a handle portion, a jaw portion, and an intermediate pivot point; a longitudinal journal in each handle portion, and a resilient locking member slideably movable through both of said journals, and means on said locking member for limiting the sliding of said locking member in both directions.

20. A hair curler including a tubular member, a longitudinal journal thereon, a locking member longitudinally slideable through said journal, and means on each end of said locking member to limit the sliding movement in either direction.

25. A hair curler including a tubular member, a longitudinal journal thereupon, a locking member longitudinally slideable through said journal, and means for limiting the sliding movement of said locking member in either direction.

30. WILLIAM H. SCHMITT.
